UNITED STATES PATENT OFFICE

CLAS S. LARSON, OF MILWAUKEE, WISCONSIN, ASSIGNOR TO A. O. SMITH CORPORATION,
OF MILWAUKEE, WISCONSIN, A CORPORATION OF NEW YORK

PACKING APPLIANCE FOR PIPE TESTING

Application filed February 17, 1928. Serial No. 254,958.

The invention relates to an appliance for packing a pipe which is to be hydraulically tested, and has for its purpose to provide a pipe packing structure having a water seal 5 the efficiency of which is adapted to increase with the increase of pressure of water attempting to leave the pipe by way of the water seal, whereby the tendency of the high water pressures employed in pipe testing can 10 be toward maintaining, rather than toward breaking down or destroying the water seal.

The novel features of my invention and the manner in which it is reduced to practice will 15 become apparent from the full description of the embodiment of the invention set forth in the drawing merely for the purpose of illustration.

The single view of said drawing discloses, 20 partially in section, partially in elevation, and partially broken away, a pipe to be hydraulically tested, and also shows, partially in section, partially in elevation, and partially broken away, appliances made in accordance with my invention and associated 25 with said pipe.

With regard to the drawing and the numerals of reference thereon, 10 represents a pipe to be hydraulically tested, and 11 and 30 12 indicate, generally, packing appliances having the characteristics of my invention, there being an appliance about each of the opposite ends of the pipe.

So far as the essential features of the invention are concerned, the appliances 11 and 35 12 may be duplicates, but when adapted to use, they are slightly different, one having an inlet for water, and the other being solid except for an outlet for air, as will be understood.

40 As disclosed, the packing appliance 11 is about the water inlet end portion of the pipe. A block 13 of this appliance is adapted to be stationarily supported, as by a fixture 14, and is provided with a water inlet 15 leading 45 to the interior of the pipe.

An annular shoulder 16 of the block 13 is adapted to surround the adjacent end portion of the pipe in spaced relation thereto, to provide an annular chamber 17, about said adjacent end portion of the pipe, defined by

an annular flat outer wall 18 concentric with the pipe, and an annular desirably flat base 19 perpendicular to the wall 18.

A packing ring support consists of a disc 55 which comprises an annular element 20 adapted to rest against the base 19 and desirably engage the wall 18, an integral upstanding annular neck 21 upon the annular element and extending beyond the shoulder 16, in spaced relation to, and preferably concentric with, the wall 18 and the pipe, and having preferably a well rounded annular head or bead 22 upon the neck and parallel with the base 19. Ports 23 in the annular neck 21 are to allow passage of water through 60 the packing ring support to the part of the annular chamber at the side of said support opposite the pipe.

The inner face of the base 24 of an annular U-shaped packing ring of suitable material, 70 such as leather, is adapted to rest against the annular head or bead 22 of the ring support, while the spaced apart legs 25 and 26 of said packing ring extend into the chamber 17 in such manner that the outer face of the leg 75 25 snugly encircles the surface of the pipe and the outer face of the leg 26 bears snugly against the annular wall 18 of the shoulder 16.

A packing ring retainer 27 consists of an 80 annular plate having a flanged surface 28 adapted to fit against a corresponding surface of the shoulder of the block 13, and an annular groove 29 adjacent the flanged surfaces and adapted to fit, when said surfaces are in engagement, against the outer face of the base 24 and a portion of the leg 26 of the annular U-shaped packing ring, to insure the fixed position of said ring. Any convenient means may be utilized to secure the retainer 27 to the block 13, as, for example, screw bolts 30 (only one being shown).

The packing appliance 12 at the end of the pipe opposite its inlet, may be similar to the appliance 11 already described, except that the block 13' is solid, or is closed, at the location which corresponds to the water inlet of the block 13, and that said block 13' has an ordinary air outlet 31, desirably at the longitudinal or transverse top of the pipe, and pro- 95 100

vided of course, with shut-off means (not shown). The block 13' is adapted to be stationarily supported, in a manner for example, similar to that of supporting the block 13, while the testing is being accomplished.

5 Water which enters the chamber 17, beneath the packing ring, in an attempt to leave the pipe, will cause the legs 25 and 26 of said packing ring to engage the pipe wall and the annular wall 18, respectively, under pressure commensurate with the water pressure, as will be obvious, so that the tendency of the high water pressures employed when testing pipes will be toward the maintenance of the 10 water seal, rather than toward the destruction 15 thereof, as has heretofore been the case.

Having thus described my invention, what I claim and desire to secure by Letters Patent of the United States, is:

20 1. A packing appliance for pipes to be hydraulically tested, comprising a block adapted to be in proximity to an end of a pipe and having a shoulder surrounding the adjacent end portion of said pipe in spaced relation thereto to provide an annular chamber between said pipe end portion and an annular wall of said shoulder concentric with said pipe, an annular packing ring support associated with said block and situated at 25 least partially in said chamber in spaced and concentric relation to said pipe and said annular shoulder wall, an annular packing ring of general U-shape in cross-section having the inside face of its base resting against said 30 support and its legs situated in spaced apart relation to each other, the outer face of one of said legs snugly encircling said pipe and at least a part of the outer face of the other of said legs snugly engaging said annular 35 wall of said chamber, and a retainer fixing said annular packing ring relatively to said pipe and said annular wall.

2. A packing appliance for pipes to be hydraulically tested, comprising a block adapted to be in proximity to an end of a pipe and having a shoulder surrounding the adjacent end portion of said pipe in spaced relation thereto to provide an annular chamber about 40 said pipe end portion and defined by an annular wall of said shoulder concentric with said pipe and an annular base constituted by a surface of said block within the confines of said annular shoulder wall, an annular packing ring support resting against the annular base of said chamber and situated in 45 spaced and concentric relation to said pipe and said annular shoulder wall, an annular packing ring of general U-shape in cross-section having the inside face of its base resting 50 against the outer edge of said support and its legs situated in spaced apart relation to each other, the outer face of one of said legs snugly encircling said pipe and at least a part of the outer face of the other of said 55 legs snugly engaging said annular wall of

said chamber, and a retainer fitted against the outer face of the packing ring to fasten said ring and its support in fixed relation to said pipe, said annular wall, and said chamber base.

3. A packing appliance for pipes adapted to prevent a leakage of fluid under internal pressure therefrom comprising an annular member adapted to encase an end of said pipe and having an inwardly extending recess, 75 the walls of said recess together with the walls of said pipe defining an annular chamber, means for transmitting the internal pressure of said pipe to said chamber, an annular U-shaped sealing member in said chamber, the base of said U-shaped member and one of the legs thereof closely engaging the walls of said recess, the other leg of said U-shaped member closely engaging the wall of said pipe whereby the internal pressure of said pipe tends to maintain a fluid seal and prevent leakage of the fluid from said pipe.

4. A packing appliance for pipes adapted to prevent leakage of fluid under internal pressure therefrom comprising an annular member adapted to encase the end of the pipe walls and having an inwardly extending recess, the walls of said recess and said pipe defining an annular chamber, a flexible U-shaped sealing member in said chamber, the base and one leg of said U-shaped member closely engaging the walls of said recess and the other leg of said U-shaped member closely engaging the walls of said pipe, a supporting member for said sealing member in said chamber adapted to retain said sealing member in position, means for transmitting internal pressure of said pipe to said chamber to press said U-shaped sealing member into tight engagement with the walls of said recess and pipe to prevent leakage of the fluid from said pipe.

5. A packing appliance for pipes adapted to prevent leakage of the internal pressure therefrom comprising an annular member spaced from the end walls of the pipe to define an annular recess, a flexible U-shaped annular sealing member in said recess, one leg of said U-shaped member engaging the inner wall of said first named annular member, the outer leg of said U-shaped member engaging the outer wall of said pipe, and closure means for said recess adapted to maintain said U-shaped sealing member in position whereby the internal pressure of the fluid is exerted against the inner walls of said U-shaped member to provide an effective seal against leakage of fluid from said pipe.

6. A packing appliance for pipes comprising an annular member having a base portion, an inwardly extending recessed shoulder in said annular member, said shoulder encasing the end of said pipe, a U-shaped resilient sealing member in said recess, one leg of said U-shaped sealing mem-

ber engaging the wall of said recess and the other leg of said U-shaped member engaging the wall of said pipe, closure means for said recess to maintain said sealing member in position, means for transmitting the internal pressure of said pipe to said recess whereby said pressure is exerted against the inner walls of said U-shaped member to thereby maintain a tight fluid seal.

10 7. A packing appliance for pipes comprising a base portion having an annular shoulder concentric with said pipe walls and outwardly spaced therefrom to define with said pipe walls an annular recess, a U-shaped flexible sealing member in said recess, means to support said U-shaped sealing member in said recess, a retainer ring engaging said shoulder and said pipe wall for holding said sealing member in said recess, means for 20 transmitting the internal pressure of said pipe to said recess, whereby said pressure is exerted against the inner walls of said U-shaped sealing member to maintain a tight seal and prevent leakage between the walls 25 of said sealing member and said pipe.

In testimony whereof I have signed my name at Milwaukee, Wisconsin, this 8th day of February, 1928.
